US00D620013S

(12) **United States Design Patent**
Chang et al.

(10) **Patent No.:** US D620,013 S
(45) **Date of Patent:** ** Jul. 20, 2010

(54) **KEYBOARD**

(75) Inventors: **Yu-Hsien Chang**, Tao Yuan (TW); **Allen Ming-kuang Han**, Bellevue, WA (US); **Ming-Hsiang Yen**, Tao Yuan (TW); **Hung-Chih Chen**, Tao Yuan (TW)

(73) Assignee: **HTC Corporation**, Taoyuan County (TW)

(**) Term: **14 Years**

(21) Appl. No.: **29/304,115**

(22) Filed: **Feb. 26, 2008**

(51) **LOC (9) Cl.** **14-02**

(52) **U.S. Cl.** **D14/455**

(58) **Field of Classification Search** **D14/454,**

D14/455, 456, 315, 320, 331, 333, 334, 338, D14/339, 341, 342, 343, 344, 345, 346, 347, D14/387, 390, 391, 392, 393, 394, 395, 396, D14/397, 398, 399, 400, 401, 406, 429, 432, D14/439, 457, 460, 461, 247, 150, 218, 900, D14/901, 902, 137, 138 R, 138 AA, 138 AB, D14/138 AC, 138 AD, 138 C, 138 G; D21/333, D21/329, 331; D18/1, 2, 7, 52, 25, 29; D13/138, D13/171; 400/88, 109, 110, 111, 484, 485, 400/486, 487, 488, 490, 492, 493, 494, 496, 400/904; 345/168, 169, 170, 171; 455/556.1, 455/556.2; D20/11, 22, 27

(57) **CLAIM**

The ornamental design for a keyboard, as shown and described.

DESCRIPTION

The FIGURE is a front elevational view of a keyboard depicting our new design.

The broken line adjacent to the graphical indicia defines the bounds of the claimed design and forms no part thereof. All other broken lines are included for the purpose of illustrating the remainder of the keyboard and found no part thereof.

1 Claim, 1 Drawing Sheet
